[57] CLAIM

The ornamental design for a book stand, as shown and described.

DESCRIPTION

FIG. 1 is a perspective view of the book stand in accordance with the invention;

FIG. 2 is a top plan view of the book stand in accordance with the invention;

FIG. 3 is a front view in elevation of the book stand in accordance with the invention;

FIG. 4 is a side view in elevation of the book stand as illustrated in FIG. 3; and

FIG. 5 is a bottom view of the book stand in accordance with the invention.

The side of the book stand not shown is a mirror image of the side shown in FIG. 4.
